UNITED STATES PATENT OFFICE.

JOHN P. SPENCER, OF SOUTH PUEBLO, COLORADO.

GOLD-WASHER.

SPECIFICATION forming part of Letters Patent No. 272,738, dated February 20, 1883.

Application filed September 30, 1882. (No model.)

To all whom it may concern:

Be it known that I, JOHN P. SPENCER, a citizen of the United States, residing at South Pueblo, in the county of Pueblo and State of Colorado, have invented certain new and useful Improvements in Gold-Washers, of which the following is a specification, reference being had therein to the accompanying drawings.

My invention has relation to gold-washers; and it consists in the construction and arrangement of its several parts, as will be hereinafter fully set forth, and pointed out in the claims.

In the drawings, Figure 1 is a perspective view of my washer, and Fig. 2 is a vertical longitudinal section of the same.

A represents the box or frame to which the operating parts of the machine are secured, as shown. Secured across the sides of the upper portion of the frame is an inclined board, *a*, between the lower end of which and the end of the frame is a space sufficiently wide for the passage of sand, &c., into the tank.

At the top of the frame, and sliding on ways, (not shown,) is a reciprocating sieve, *B*, which inclines in the opposite direction from that of the board *a*. From the front end of the sieve depends an arm, *b*, to the lower end of which is pivoted the rod *b'*, said rod having its opposite end journaled on the actuating-shaft *C*, which revolves between the arms *c*, attached to the sides of and projecting from the ends of the frame, as shown.

D is the tank in which the sand is washed. It slides upon the bottom of the frame, and its rear end is cut away at *d* to permit the escape of surplus water and gravel and the removal of the agitator-shaft. The bottom of the tank is made laterally semicircular, in order that the same be made to move readily to gravitate toward the rear end by the action of the agitators.

Pivoted to a suitable projection, *d*, on the upper portion of the front end of the box is a connecting-rod, *d'*, the opposite end of which is journaled to the crank-shaft, whereby motion is transmitted to the tank.

Journaled between the ends of the frame

A', which is secured to the sides of the box, as shown, and passing through the tank, is the agitator-shaft *E*, from which project the agitators *e*. Upon the front end of the shaft is secured a pulley, *F*, which communicates, by a belt or chain, *H*, with a pulley, *G*, on the shaft *C*, as shown, so that when the shaft is revolved motion is transmitted to the shaft *E*.

In the operation of the washer the actuating-shaft *C* is turned by the crank *I*, or by suitable connections.

The sieve *B* is reciprocated by the rod *b'*, the tank *D* by the rod *d'*, and the agitator-shaft revolved by means of the pulleys *F* and *G* and the chain *H*.

It is well known among miners that gold-washing machines are only used to wash the sand along river-bottoms and from the beds of small streams, and that consequently the sand contains more or less water. The wet sand is dumped onto the sieve, and the lumps too coarse to pass through the meshes are shaken over the rear of the machine. The sand which passes through the meshes of the sieve is washed down the inclined board *a* by the water which drips onto it from the sand in the sieve *B*, situated above the board, and falls over the edge of said board to the bottom of the tank. The revolving agitators are inclined, so as to carry the sand toward the rear end of the tank and thoroughly mix or stir it, so that the gold contained therein gravitates toward the bottom, where it is seized upon and held by quicksilver placed in the tank. The surplus sand is carried out through the opening *d* in the rear end of the tank.

What I claim is—

1. In a gold-washing machine, the combination of a reciprocating sieve, an inclined board, a reciprocating tank, an agitator-shaft provided with suitably-arranged agitators, an actuating-shaft, and mechanism arranged thereon for reciprocating the sieve and tank and revolving the agitator-shaft, all arranged to operate substantially as shown and described.

2. The combination, in a gold-washing machine, with the box *A*, and the frame *A'*, of a reciprocating tank, actuating-shaft, a rod for

connecting said tank and shaft, an agitator-shaft having suitably-arranged agitators, said shaft being journaled in the frame secured around the box A, and having a pulley communicating by a belt or chain with a pulley on the actuating-shaft, whereby the shaft and agitators are revolved, substantially as shown and described.

In testimony whereof I affix my signature in presence of two witnesses.

JOHN P. SPENCER.
